MATRIX-SETTING AND TYPE-LINE-CASTING MACHINE.

Application filed December 27, 1927, Serial No. 242,862, and in Germany April 18, 1925.

This invention is for improvements in or relating to matrix-setting and type-line casting machines of the kind wherein the matrices are assembled in a line by feeding mechanism which presses the matrices into a guideway against an assembling-abutment which is movable in the direction of the length of the line and wherein the assembled line of matrices is moved towards the mould by a transferring-abutment. It is usual in this kind of machine for the assembled line of matrices to be conveyed between the assembling-abutment and the transferring-abutment to the casting-carriage, and for these two abutments to be returned to their initial positions after the carriage has been moved towards the mould. It will be seen that with such an arrangement a new line of matrices cannot be assembled until the assembling-abutment has been returned to its initial position.

An object of this invention is to provide a construction which will permit a line of matrices to be assembled while the previous line is on its way to the casting-carriage or to the mould.

According to this invention, a matrix-setting and type-line casting machine of the kind described is characterized in that means are provided for automatically withdrawing the assembling-abutment from in front of an assembled line of matrices and for returning it to its initial position before or during the transference of the line, and in the provision of a forward transferring-abutment which is arranged to replace the assembling-abutment when the latter is withdrawn, which forward transferring-abutment, together with the first said and rearward transferring-abutment, conveys the assembled line of matrices towards the mould. Means are provided for automatically withdrawing the said transferring-abutments from contact with the line of matrices before the casting-carriage is moved and means for returning the transferring-abutments to their initial positions.

In order that the forward transferring-abutment may replace the assembling-abutment these two parts are so disposed in relation to one another and so formed that they may be made to engage at the same time the forward end of the assembled line of matrices, for example one of them may be slotted

and the other arranged to enter the slot. 55 Preferably the assembling-abutment is withdrawn after or at the time of the engagement of the forward transferring-abutment with the line of matrices.

A convenient arrangement for withdrawing the assembling-abutment at the required time from in front of the line of matrices consists in forming the said assembling-abutment as a finger pivotally mounted upon a carriage which is guided to move in the direction of the length of the line of matrices and in providing a stop carried on a fixed part of the machine and so disposed in the path of travel of a part of the said finger as to swing the finger clear of the line of matrices when the line is being moved towards the casting-carriage. The details of the construction of said finger are clearly set out in the accompanying description of one embodiment of this invention. 75

The forward transferring-abutment also preferably comprises a finger pivotally mounted upon a carriage which is arranged to move in the direction of the length of the line of matrices, which finger is retained in contact with the matrices by means of a pawl until after the line has been conveyed into the casting-carriage whereupon a fixed stop releases the pawl and the finger is swung away from the matrices under the action of a spring. 80

Other features of the invention will be apparent from the following description of one embodiment of this invention.

In the following description of a matrix-setting and type-line casting machine, reference is made to the accompanying drawings, in which—

Figure 1 is a side elevation of the part of the machine in which the matrices are fed into the assembling-guide and also the casting-carriage which delivers them to the mould, not shown. The parts are in position ready for transferring the line to the casting-carriage; 95

Figure 2 shows an end elevation of the construction of Figure 1 with certain parts in section;

Figure 3 shows a similar view of the machine to Figure 1 but with the line of matrices engaged by the two transferring-abutments and with the assembling-abutment withdrawn therefrom; 105

Figure 4 is a plan view of the arrangement of Figure 1 showing certain parts in section;

Figure 5 is a plan view of the arrangement of Figure 3 also showing certain parts in section;

Figure 6 is a similar view to Figure 1 but showing the line of matrices in position in the casting-carriage with the forward transferring-abutment out of contact therewith;

Figure 7 is a similar view to Figure 6 showing the casting-carriage at the commencement of the downward movement towards the mould and about to release the forward transferring-abutment so that it may be returned to its initial position;

Figures 8, 9, 10 and 11 show details of construction of the assembling-abutment and the relative positions of the various parts during a state of rest and during the movement for its withdrawal from the line of matrices;

Figures 12 and 13 show details of construction of the forward transferring-abutment;

Figures 14 and 15 show an alternative form of the forward transferring-abutment and the means for disengaging it from the line of matrices and releasing it so that it may be returned to its initial position.

The matrices after being released from their respective magazines are conveyed to the horizontal assembling-guide 2 in the usual manner by means of the collecting-bridge and star-wheel 1 which latter part guides the matrices into the assembling-guide. An assembling-abutment 3 is arranged to project vertically into the said assembling-guide and the matrices are pressed by the action of the said star-wheel against the said assembling-abutment. The assembling-abutment is mounted on an assembling carriage 4 which is arranged to slide horizontally and the movement given to the abutment through the agency of the star-wheel and line of matrices is opposed by a spring 6 acting through a lever 5 secured to the said carriage. Thus when the abutment is withdrawn from the line of matrices the spring returns it to its initial position.

The construction of the assembling-abutment, as shown in Figures 8 to 11, comprises an upright member 7 which is secured to the assembling-carriage 4 and carries towards its upper end a horizontal shaft 8 which is arranged transversely above the said assembling-guide. An assembling finger 3 is carried at one end of said shaft and projects downwardly into the said assembling-guide. To the other end of the shaft is attached a two-armed lever 9, 12, of which the arm 9 carries an adjusting-screw 10 which cooperates with a stop 11 carried by the said upright member. The said assembling

finger can thus be adjusted to take up an exact vertical position. On the other arm 12 there is pivotally mounted at 14 a stop plate 13. Said stop plate is provided with a curved slot 15, the curve of which is concentric with the pivot 14. A pin 18 formed at the end of the shaft projects through the said slot. The said stop plate is pulled downwardly by means of a spring 17 which is secured in such a manner to the said plate that the left-hand end of the slot, as viewed in Figure 9, is maintained in contact with the said pin. A lug 16 is formed on the said plate above the slot, as viewed in Figure 9, which shows the position of the assembling finger 3 at a time when it is supporting the line of matrices. The bottom of the plate at the right-hand side 19 is arranged to engage with an adjustable stop 20 carried by the said upright 7.

When the matrices are being pressed during the building up of the line against the assembling finger in a direction shown by the arrow X in Figure 9, the finger is prevented from being moved outwardly by reason of the fact that the side 19 abuts against the said adjustable stop 20. When the assembled line of matrices is conveyed towards the casting-carriage in the direction as indicated by the arrow Y in Figures 9, 10 and 11, the lug 16 engages a stop 28 (shown in Figures 1 to 3) carried by a fixed part of the machine; the assembling carriage 4 is thus arrested and the stop plate 13 is caused to turn about the pin 14 until the pin 18 contacts with the right-hand end of the slot as shown in Figure 10 at which time the right-hand bottom side is withdrawn from the adjustable stop 20. Continued movement of the assembling carriage causes the stop plate 13 to rotate the shaft 8 whereby the finger 3 is swung upwardly out of the assembling-guide, as shown in Figure 11 so that the line of matrices is now able to pass below the said finger. At this moment the forward end of the line of matrices is engaged by the forward transferring-abutment 30. When the whole line has passed below the assembling finger the latter is pulled back into the vertical position by the spring 17 and the assembling carriage 4 is withdrawn to its original position by the spring 6 as already set forth. The finger is thus once more ready to form a new line of matrices. The line of matrices is moved into the casting-carriage by means of the rearward transferring-abutment which comprises a rearward-finger 21 pivotally mounted upon a rearward transferring carriage 22. While the line of matrices is being assembled the finger 21 is held in a position below the star-wheel 1 by a spring-controlled pawl 23 which is mounted on the carriage 22. Movement is given to the carriage 22 for the purpose of conveying the line of matrices to the casting-carriage mov-

ing means 24. A projection 25 on the moving means is arranged at the commencement of the movement of the chain to engage the pawl 23. The finger 21 is thereby released 5 and is pushed upwardly by the said spring so as to engage the rearward end of the assembled line of matrices, as shown in Figure 3.

As already stated, at the moment at which the finger of the assembling-abutment is 10 swung away from the line of matrices the forward end of the said line is engaged by the finger of the forward transferring-abutment 30 which together with the finger 21 of the rearward transferring-abutment holds the 15 line together.

The construction of the forward transferring-abutment is shown in Figures 12 and 13 and comprises a forward transferring finger 30 which is mounted on a pin 36 carried horizontally by the forward transferring carriage 31. The carriage is guided to move horizontally towards the casting-carriage which movement is opposed by a helical tension spring 32. As shown in Figures 25 4 and 5, said spring is secured at its forward end to a part of the carriage and towards its rearward end passes through a bore in a lug 33 carried by a fixed part of the machine. The said bore is internally 30 threaded so as to engage the convolutions of the spring. The said spring projects rearwardly from the said lug. Located axially within the said spring is a rod 35 the forward end of which, when the carriage is 35 in its rearward position, rests against a part of the carriage, and the rearward end of which pin is connected to the end of the spring which projects rearwardly from the said lug. The spring and rod are enclosed 40 within a tube-shaped channel 34. It will be seen with this arrangement that the rearward end of the spring may be arranged to act as a buffer for the rearward return movement of the carriage. Alternatively, 45 the spring 32 may be made in two parts so that the tension spring attached to the carriage and the buffer spring attached to the right-hand end of the pin 35 are mounted in the lug 33 so as to be independent of one 50 another. The forward transferring finger 30 is held in a vertical position by a pawl 37 ready for engaging the forward end of the assembled line of matrices, which end is released from the assembling-abutment 55 finger 3, as shown in Figure 13. The said pawl is mounted on the forward transferring carriage 31 and engages with a recess 38 formed in the finger 30, and is retained in position by a spring. The said finger 30 is held in a vertical position until the 60 assembled line of matrices has been conducted to the furthest forward position in the casting-carriage. As soon as this position has been reached the carriage is locked 65 against movement, as shown in Figure 6,

by a pawl 39 which is spring-pressed into engagement with a recess 40 formed in the carriage 31, the said pawl being carried on a fixed part of the machine; simultaneously the pawl 37 is moved out of engagement 70 with the recess 38 in the finger 30 by means of a stop 41 also carried on a fixed part of the machine. The said finger 30 is then swung forwardly away from the line of matrices by means of a spring-actuated pin 42 75 which is carried by the carriage 31. The movement of the said finger 30 is limited by the pawl 37 engaging with a second recess 43 therein. In this manner the forward end of the line of matrices is released from the 80 said finger. At the moment that the forward end of the line of matrices is released, the finger 21 is withdrawn from the rearward end of the line and is conducted back to its original position. On the rearward 85 journey of the finger 21 it passes beneath the finger 3 which is then directed vertically downwards and is swung downwardly by the said finger 3 and locked in this downward position by the pawl 23, and in this 90 position turns to beneath the star-wheel.

The line of matrices now in the casting-carriage is conducted into the casting position by the downward movement of said carriage, as shown in Figure 7. As the carriage descends a stop 46 thereon engages with a tail-piece 44 formed on the finger 30 and tilts the latter part back again to its original vertical position against the resistance of the spring pin 42 and is locked again 100 in this position by the engagement of the pawl 37 with the recess 38. During the continued descent of the casting-carriage the stop 46 engages with the pawl 39 and releases it from the recess 40 in the carriage 105 31 so that the latter is pulled back into its original position by the spring 32.

In Figures 14 and 15 an alternative construction is shown for the forward transferring abutment. A forward transferring finger 30^a is mounted on a horizontal shaft 90 which is spring-pressed in a direction towards the forward end of the line of matrices. The forward end of the shaft is engaged by one end of a double lever 91 which is mounted on the carriage 31. When the assembled line of matrices is conveyed into the casting-carriage the movement of the carriage 31 causes the other end of the lever 91 to be engaged by the stop 41 whereby 110 the shaft 90 and finger 30^a are withdrawn, against the action of the spring, away from the front of the line of matrices. The carriage 31 is retained in position at the end of its travel by reason of a vertical spring-pressed pin 93 which is mounted on the carriage snapping over the end of a bell-crank lever 95. The said end of the bell-crank lever 115 is spring-pressed upwardly by a spring 94, which spring is of less strength than the 120

spring of the vertical pin. The stop 46 on the casting-carriage is arranged on the downward movement thereof to engage the inclined face on the upwardly-directed arm 96 of the bell-crank lever whereby the arm 95 is lowered against the action of the spring 94 and the spring-pressed pin 93 is pulled past it and releases the carriage 31. The second transferring-abutment is then again 10 automatically restored to its initial position.

We claim:

1. In a matrix-setting and line casting machine, mechanism for building up a line of matrices and for transferring it towards a casting position, comprising in combination, an assembling-abutment, means for feeding the matrices against said abutment so that it moves toward casting position during the formation of said line, a rearward transferring abutment arranged to engage the rear end of a completed line of matrices, means for withdrawing the assembling-abutment from in front of the line when the line is complete and for returning it to its initial position, a forward movable transferring-abutment arranged to support the end of the line freed by said assembling-abutment which two transferring abutments are arranged to convey the line of matrices between them towards the casting position.
2. In a matrix-setting and line casting machine, mechanism for building up a line of matrices and for transferring it towards a casting position, comprising in combination, a movable assembling abutment, means for feeding the matrices against said abutment so that it moves towards the casting position during the formation of the line, a rearward transferring abutment arranged to engage the rear end of a completed line of matrices, means operable by the movement of said assembling abutment for automatically withdrawing the latter from in front of the line when the line is complete and for returning it to its initial position, a forward movable transferring-abutment arranged to support the end of the line freed by said assembling-abutment which two transferring abutments are arranged to convey the line of matrices between them towards the casting position.
3. In a matrix-setting and line casting machine, mechanism for building up a line of matrices and for transferring it towards a casting position, comprising in combination, an assembling-abutment, means for feeding the matrices against said abutment to form said line, a rearward transferring abutment arranged to engage the rear end of a completed line and move it towards the mould, a forward transferring-abutment arranged when the line is complete to cooperate with the assembling-abutment to support said line, fixed means engageable by said assembling-abutment when the line is

moved towards the casting position to withdraw said assembling abutment from said line, and means for returning it to its initial position.

4. In a matrix setting and line casting machine, mechanism for building up a line of matrices and for transferring it towards a casting position, comprising in combination a slotted assembling-abutment, means for feeding the matrices against said abutment to form said line, a rearward transferring abutment arranged to engage the rear end of a completed line of matrices, means for automatically withdrawing the assembling-abutment from in front of the line when the line is complete and for returning it to its initial position, a forward movable transferring-abutment arranged to be accommodated in said slotted assembling-abutment, and to co-operate to support said line, freed by said assembling-abutment which two transferring abutments are arranged to convey the line of matrices between them towards the casting position.

5. In a matrix-setting and line casting machine, mechanism for building up a line of matrices and for transferring it towards a casting position, comprising in combination, an assembling finger pivotally mounted upon a movable assembling carriage, means for feeding the matrices against said finger so as to move it and its carriage towards the casting position, means for retaining said finger during the formation of the line in a correct position to support the matrices, a rearward transferring abutment arranged to engage the rear end of a completed line of matrices, means for swinging said finger away from the matrices when the line is complete and for returning it to its initial position, a forward movable transferring abutment arranged to support the end of the line freed by said assembling-abutment which two transferring abutments are arranged to convey the line of matrices between them towards the casting position.

6. In a matrix-setting and line casting machine, mechanism for building up a line of matrices and for transferring it towards a casting position, comprising in combination an assembling finger pivotally mounted upon a movable assembling carriage, means for feeding the matrices against said finger so as to move it and its carriage towards the casting position, means for retaining said finger during the formation of the line in a correct position to support the matrices, a rearward transferring abutment arranged to engage the rear end of a completed line of matrices and to move it and the movable carriage towards the casting position, a stop carried on a fixed part of the machine and so disposed in the path of travel of a part of said finger as to swing the finger clear of said line of matrices when the assembling

carriage is moved by said transferring abutment, means for returning said finger to its initial position, a forward movable transferring abutment arranged to support the end of the line freed by said assembling-abutment which two transferring abutments are arranged to convey the line of matrices between them towards the casting position.

7. In a matrix-setting and line casting machine, mechanism for building up a line of matrices and for transferring it towards a casting position, comprising in combination an assembling finger fixed to a rock shaft carried by a movable assembling carriage, a stop plate so mounted as to have limited motion on said rock shaft and so as to rotate said rock shaft when moved beyond said limits, a stop on said carriage arranged to hold the stop plate and finger in a correct position for building up a line of matrices, means for feeding the matrices against said finger whereby the finger and its carriage are moved towards the casting position, a rearward transferring abutment arranged to engage the rear end of a completed line of matrices and move it, the carriage and the parts thereon towards the casting position, a fixed stop arranged to engage the stop plate during the latter movement and move it clear of the stop on the carriage and then cause it to swing the assembling finger away from the line of matrices, means for returning said assembling carriage to its initial position, a forward movable transferring abutment arranged to support the end of the line freed by said assembling-abutment which two transferring abutments are arranged to convey the line of matrices between them towards the casting position.

8. In a matrix-setting and line casting machine, mechanism for building up a line of matrices and for transferring it towards a casting position, comprising in combination an assembling finger fixed to a rock shaft carried by a movable assembling carriage, a stop plate so mounted as to have limited motion on said rock shaft and so as to rotate said rock shaft when moved beyond said limits, a stop on said carriage arranged to hold the stop plate and finger in a correct position for building up a line of matrices, an arm fixed on said rock shaft, a stop carried on said assembling carriage and arranged to contact with said arm for the purpose described, means for feeding the matrices against said finger whereby the finger and its carriage are moved towards the casting position, a rearward transferring abutment arranged to engage the rear end of a completed line of matrices and move it, the carriage and the parts thereon towards the casting position, a fixed stop arranged to engage the stop plate during the latter movement and move it clear of the stop on

the carriage and then cause it to swing the assembling finger away from the line of matrices, means for returning said assembling carriage to its initial position, a forward movable transferring abutment arranged to support the end of the line freed by said assembling-abutment which two transferring abutments are arranged to convey the line of matrices between them towards the casting position.

9. In a matrix-setting and line casting machine, mechanism for building up a line of matrices and for transferring it towards a casting position, comprising in combination an assembling finger fixed to a rock shaft carried by a movable assembling carriage, a crank-arm on said rock shaft, a stop plate pivoted to said crank-arm the axis of which pivot is parallel to the rock shaft, a curved slot in said stop plate through which an extension of the rock shaft passes, a stop on said carriage arranged to engage a part of the stop plate so as to locate it and the finger in the correct position for building a line of matrices, means for feeding the matrices against said finger whereby the finger and its carriage are moved towards the casting position, a rearward transferring abutment arranged to engage the rear end of a completed line of matrices and move it, the carriage and the parts thereon towards the casting position, a fixed stop arranged to engage the stop plate during the latter movement and move it clear of the stop on the carriage and then cause it to swing the assembling finger away from the line of matrices, means for returning said assembling carriage to its initial position, a forward movable transferring abutment arranged to support the end of the line freed by said assembling-abutment which two transferring abutments are arranged to convey the line of matrices between them towards the casting position.

10. In a matrix-setting and line casting machine, mechanism for building up a line of matrices and for transferring it towards a casting position, comprising in combination an assembling finger fixed to a rock shaft carried by a movable assembling carriage, a crank arm on said rock shaft, a stop plate pivoted to said crank arm the axis of which pivot is parallel to the rock shaft, a curved slot in said stop plate through which slot an extension of the rock shaft passes, a stop on said carriage arranged to engage a part of the stop plate so as to locate it and the finger in the correct position for building a line of matrices, an arm fixed on said rock shaft, an adjustable stop disposed between said arm and the carriage, a spring secured between said stop plate and carriage so as to maintain one end of the slot in contact with the extension of the rock shaft and maintain the arm on said

- rock shaft in contact with the adjustable stop and carriage, a rearward transferring abutment arranged to engage the rear end of a completed line of matrices and move it, the carriage and the parts thereon towards the casting position, a fixed stop arranged to engage the stop plate during the latter movement and move it clear of the stop on the carriage and then cause it to swing the assembling finger away from the line of matrices, means for returning said assembling carriage to its initial position, a forward movable transferring abutment arranged to support the end of the line freed by said assembling-abutment which two transferring abutments are arranged to convey the line of matrices between them towards the casting position.
11. In a matrix-setting and line casting machine, mechanism for building up a line of matrices and for transferring it towards casting position, comprising in combination, an assembling-abutment, means for feeding the matrices against said abutment so that it moves toward casting position during the formation of said line, a rearward transferring abutment arranged to engage the rear end of a completed line of matrices, means for withdrawing the assembling-abutment from in front of the line when the line is complete and for returning it to its initial position, a forward movable transferring-abutment arranged to support the end of the line freed by said assembling-abutment which two transferring abutments are arranged to convey the line of matrices between them towards the casting position, a casting-carriage which is movable towards the casting position and to which the line is conveyed by said transferring abutments, means for automatically withdrawing both said transferring-abutments from the line after it has been accommodated in said casting carriage and means for returning said transferring-abutments to their initial positions.
12. In a matrix-setting and line casting machine, mechanism for building up a line of matrices and for transferring it towards casting position, comprising in combination, an assembling-abutment, means for feeding the matrices against said abutment to form said line, a rearward transferring abutment arranged to engage the rear end of a completed line of matrices, means for automatically withdrawing the assembling-abutment from in front of the line when the line is complete and for returning it to its initial position, a forward movable transferring-abutment arranged to support the end of the line freed by said assembling-abutment which two transferring abutments are arranged to convey the line of matrices between them towards the casting position, a casting-carriage adapted to accommodate

the line of matrices and transfer them to a casting position, means for releasing the rearward transferring-abutment from the line of matrices and for returning it to its initial position when the line has been accommodated in said carriage, means for disengaging the forward transferring-abutment from the line and for retaining it in a fixed position until the carriage has been moved towards the casting position, and means for returning said forward transferring-abutment to its initial position.

13. In a matrix-setting and line casting machine, mechanism for building up a line of matrices and for transferring it towards a casting position, comprising in combination, an assembling-abutment, means for feeding the matrices against said abutment to form said line, a rearward transferring abutment arranged to engage the rear end of a completed line of matrices, means for automatically withdrawing the assembling-abutment from in front of the line when the line is complete, a forward transferring carriage located at the forward end of the line of the matrices, means to guide said forward transferring carriage towards the moulding position, a forward transferring finger movably mounted on said forward transferring carriage and arranged to support the end of the line of matrices when the line is freed by said assembling abutment, a casting carriage which is movable towards the casting position and to which the line is transferred by the rearward transferring abutment and forward transferring finger, a stop located near the forward end of said casting carriage for moving the forward transferring finger away from the line of matrices, and means for returning the forward transferring abutment and carriage to their initial positions.

14. In a matrix-setting and line casting machine, mechanism for building up a line of matrices and for transferring it towards a casting position, comprising in combination, an assembling-abutment, means for feeding the matrices against said abutment to form said line, a rearward transferring abutment arranged to engage the rear end of a completed line of matrices, means for automatically withdrawing the assembling-abutment from in front of the line when the line is complete, a forward transferring-carriage located at the forward end of the line of matrices, means to guide said forward transferring carriage towards the moulding position, a forward transferring finger pivotally mounted on said forward transferring carriage, a detent on said carriage for holding said finger in a position to support the forward end of the line of matrices freed by said assembling abutment, a casting carriage which is movable towards the casting position and to which the line of matrices is

transferred by the rearward transferring abutment and forward transferring finger, a stop located near the forward end of said casting carriage and arranged to release said 5 detent and means on said carriage for moving said forward transferring finger when released by said detent away from the line of matrices, and means for returning the rearward transferring abutment and forward 10 transferring carriage to their initial positions.

15. In a matrix-setting and line casting machine, mechanism for building up a line of matrices and for transferring it towards a casting position, comprising in combination an assembling-abutment, means for feeding the matrices against said abutment to form said line, a rearward transferring abutment arranged to engage the rear end 20 of a completed line of matrices, means for automatically withdrawing the assembling-abutment from in front of the line when the line is complete, a forward transferring-carriage located at the forward end of the line 25 of matrices, means to guide said forward transferring carriage towards the moulding position, a forward transferring finger pivotally mounted on said forward transferring carriage, a detent on said carriage spring 30 pressed into engagement with said forward transferring finger for holding the finger in a position to support the forward end of the line of matrices freed by said assembling-abutment, a casting carriage which is movable 35 towards the casting position and to which the line of matrices is transferred by the rearward transferring-abutment and forward transferring finger, a stop located near the forward end of said casting carriage 40 and arranged to release said detent, a spring on said forward transferring carriage arranged to move said finger away from the line of matrices when the finger is released by said detent, and means for returning the rearward transferring abutment and forward 45 transferring carriage to their initial positions.

16. In a matrix-setting and line casting machine, mechanism for building up a line of matrices and for transferring it towards a casting position, comprising in combination, an assembling-abutment, means for feeding the matrices against said abutment to form said line, a rearward transferring abutment arranged to engage the rear end 55 of a completed line of matrices, means for automatically withdrawing the assembling-abutment from in front of the line when the line is complete, a forward transferring-carriage located at the forward end of the line 60 of matrices, means to guide said forward transferring carriage towards the moulding position, a forward transferring finger movably mounted on said forward transferring carriage and arranged to support the end 65 of the line of matrices.

of the line of matrices when the line is freed by said assembling abutment, a casting carriage which is movable towards the casting position and to which the line is transferred by the rearward transferring abutment and forward transferring finger, a stop located 70 near the forward end of said casting carriage for moving the forward transferring finger away from the line of matrices, a detent arranged to hold said forward transferring carriage opposite said casting-carriage, a stop on said casting carriage arranged when said casting carriage moves to release the detent that holds said forward transferring carriage and means for returning the 75 transferring abutment and forward transferring carriage to their initial positions.

17. In a matrix-setting and line casting machine, mechanism for building up a line of matrices and for transferring it towards a casting position, comprising in combination, an assembling abutment, means for feeding the matrices against said abutment to form said line, a rearward transferring abutment arranged to engage the rear end of a completed line of matrices, means for automatically withdrawing the assembling-abutment from in front of the line when the line is complete, a forward transferring carriage located at the forward end of the line of 80 matrices, means to guide said forward transferring carriage towards the moulding position, a forward transferring finger movably mounted on said forward transferring carriage and arranged to support the end of the line of matrices when the line is freed by 85 said assembling abutment, a casting carriage which is movable towards the casting position and to which the line is transferred by the rearward transferring abutment and forward transferring finger, a stop located near the forward end of said casting carriage for moving the forward transferring finger away from the line of matrices, a detent arranged to hold said forward transferring carriage opposite said casting carriage, a stop on said casting carriage arranged when said casting carriage moves to move the forward transferring finger 90 back to its initial position and then to release said detent that holds said forward transferring-carriage, and means for returning the rearward transferring abutment and forward transferring carriage to their initial 95 positions.

18. In a matrix-setting and line casting machine, mechanism for building up a line of matrices and for transferring it towards a casting position, comprising in combination, an assembling-abutment, means for feeding the matrices against said abutment to form said line, a rearward transferring abutment arranged to engage the rear end of a completed line of matrices, means for automatically withdrawing the assembling 100 abutment, a casting carriage which is movable towards the casting position and to which the line is transferred by the rearward transferring abutment and forward transferring finger, a stop located near the forward end of said casting carriage for moving the forward transferring finger away from the line of matrices, a detent arranged to hold said forward transferring carriage opposite said casting carriage, a stop on said casting carriage arranged when said casting carriage moves to move the forward transferring finger back to its initial position and then to release said detent that holds said forward transferring-carriage, and means for returning the rearward transferring abutment and forward transferring carriage to their initial 105 positions.

- abutment from in front of the line when the line is complete, a forward transferring-carriage located at the forward end of the line of the matrices, means to guide said forward transferring carriage towards the moulding position, a movable forward transferring finger spring pressed in a direction towards the forward end of the line of matrices which it supports when the line is freed by said rearward assembling abutment, a casting carriage which is movable towards the casting position and to which the line of matrices is transferred by the rearward transferring abutment and forward transferring finger, a lever pivoted intermediate of its ends to the forward transferring carriage so that one end contacts with said forward transferring finger, a stop located near the forward end of said casting carriage and arranged to engage the other end of said lever whereby the forward transferring finger is moved away from the line of matrices and means for returning the rearward transferring abutment and forward transferring carriage to their initial position.
19. In a matrix-setting and line casting machine, mechanism for building up a line of matrices and for transferring it towards a casting position, comprising in combination, an assembling-abutment, means for feeding the matrices against said abutment to form said line, a rearward transferring abutment arranged to engage the rear end of a completed line of matrices, means for automatically withdrawing the assembling-abutment from in front of the line when the line is complete, a forward transferring-carriage located at the forward end of the line of matrices, means to guide said forward transferring carriage towards the moulding position, a movable forward transferring finger spring pressed in a direction towards the forward end of the line of matrices which it supports when the line is freed by said rearward assembling abutment, a casting carriage which is movable towards the casting position and to which the line of matrices is transferred by the rearward transferring abutment and forward transferring finger, a lever pivoted intermediate of its ends to the forward transferring carriage so that one end contacts with said forward transferring finger, a stop located near the forward end of said casting carriage and arranged to engage the other end of said lever whereby the forward transferring finger is moved away from the line of matrices, a detent arranged to hold said forward transferring carriage opposite said casting-carriage, a stop on said casting-carriage arranged when said casting-carriage moves to release said detent, and means for returning the rearward transferring abutment and forward transferring carriage to their initial positions.

20. In a matrix-setting and line casting machine, mechanism for building up a line of matrices and for transferring it towards a casting position, comprising in combination a movable assembling abutment, means for feeding the matrices against said abutment to form said line, a spring urging said assembling abutment towards said feeding means, a rearward transferring abutment arranged to engage the rear end of a completed line of matrices, means for automatically withdrawing said assembling abutment whereby said abutment is returned by said spring to its initial position, a forward movable transferring abutment arranged to support the end of the line freed by said assembling-abutment which two transferring abutments are arranged to convey the line of matrices between them towards the casting position.

21. In a matrix-setting and line casting machine, mechanism for building up a line of matrices and for transferring it towards a casting position, comprising in combination, an assembling-abutment, means for feeding the matrices against said abutment to form said line, a rearward transferring abutment arranged to engage the rear end of a completed line of matrices, means for automatically withdrawing the assembling-abutment from in front of the line when the line is complete and for returning it to its initial position, a forward movable transferring-abutment arranged to support the end of the line freed by said assembling-abutment, a spring arranged to urge said forward transferring-abutment towards the feeding means, means for moving said rearward transferring abutment together with the line of matrices, and forward transferring abutment towards the moulding position which means are also arranged to return the rearward transferring abutment alone to its initial position while the forward transferring abutment is returned by said spring.

22. In a matrix-setting and line casting machine, mechanism for building up a line of matrices and for transferring it towards a casting position, comprising in combination, an assembling-abutment, means for feeding the matrices against said abutment to form said line, a rearward transferring abutment arranged to engage the rear end of a completed line of matrices, means for automatically withdrawing the assembling-abutment from in front of the line when the line is complete and for returning it to its initial position, a forward movable transferring-abutment arranged to support the end of the line freed by said assembling abutment, a spring arranged to urge said forward transferring-abutment towards the feeding means, means for moving said rearward transferring abutment together with

the line of matrices and forward transferring abutment towards the moulding position which means are also arranged to return the rearward transferring abutment alone to its initial position while the forward transferring abutment is returned by said spring and a buffer spring disposed in the rearward extremity of the path of travel of said second transferring abutment.

23. In a matrix-setting and line casting machine, mechanism for building up a line of matrices and for transferring it towards a casting position, comprising in combination, an assembling-abutment, means for feeding the matrices against said abutment to form said line, a rearward transferring abutment arranged to engage the rear end of a completed line of matrices, means for automatically withdrawing the assembling-abutment from in front of the line when the line is complete and for returning it to its initial position, a forward movable transferring-abutment arranged to support the

end of the line freed by said assembling abutment, a helical tension spring secured at 25 one end to said forward transferring abutment and secured near the other end to a fixed part of the machine towards the feeding means, a rod located within said spring and fixed at one end thereto and resting against an abutment secured at the other end of said spring, means for moving said rearward transferring abutment together with the line of matrices and forward transferring abutment towards the moulding position which means are also arranged to return the rearward transferring abutment alone to its initial position while the forward transferring abutment is returned by 30 said spring. 35

In testimony whereof we have signed our names in this specification.

KARL RÖGER.
HANS SCHOENLEBEN.
FRITZ WALTHER.
